Primary Examiner — Kendra Leslie Hamilton*Assistant Examiner* — Amanda Christensen(74) *Attorney, Agent, or Firm* — Andrew F. Young, Esq.; Nolte Lackenbach Siegel(57) **CLAIM**

The ornamental design for a multi-socket hub, as shown and described.

DESCRIPTION

FIG. 1 is a front, top, perspective view of a multi-socket hub showing our new design.

FIG. 2 is a bottom, front perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The equal-length broken lines in the drawings depict portions of the multi-socket hub that form no part of the claimed design. The dash-dot-dash broken lines defines the boundaries of the claim.

1 Claim, 8 Drawing Sheets(56)
